CLAIM

The ornamental design for kitchen knife, as shown and described.

DESCRIPTION

1.-2. Kitchen knife

1.1 : Perspective

1.2 : Front

1.3 : Bottom

1.4 : Enlarged right view

1.5 : Partial enlarged bottom view

1.6 : Partial enlarged bottom view

1.7 : Enlarged cross-sectional view

1.8 : Back

1.9 : Top

2.1 : Perspective

2.2 : Front

2.3 : Bottom

2.4 : Back

2.5 : Partial enlarged bottom view

2.6 : Partial enlarged bottom view

2.7 : Enlarged cross-sectional view

2.8 : Right

2.9 : Top

The broken lines in the drawings form no part of the claimed designs; the dash-dotted lines in the drawings represent the unclaimed boundaries; drawing nos. 1.7 and 2.7 are vertical cross-sectional views taken along an almost central plane of the blade in each front view.
